STAPLE REMOVER OR SIMILAR ARTICLE

Joseph Bacevius, Bridgeport, Conn., assignor to Swing-line, Inc., Long Island City, N.Y., a corporation of New York

Filed Nov. 18, 1958, Ser. No. 53,411

Term of patent 14 years

(Cl. D74—1)

FIG. 1 is a side elevational view of a staple remover showing my new design;

FIG. 2 is a front perspective view thereof;

FIG. 3 is an isometric view showing the back thereof; and

FIG. 4 is a sectional view thereof taken along lines 4—4 of FIG. 3.

The dominant features of my design reside in the portions shown in full lines in the drawing.

I claim:

The ornamental design for a staple remover or similar article, as shown and described.
